ATTORNEYS

UNITED STATES PATENT OFFICE

WILLIAM LA HODNEY, OF BUFFALO, NEW YORK

COMBINED MIRROR AND TIMEPIECE

Application filed April 2, 1931. Serial No. 527,199.

This invention relates to means for attaching dial instruments to panels, and particularly to the mounting of clocks upon rear view mirrors for use in connection with motor vehicles.

An object of the invention is to improve and simplify attaching means of this type.

Another object of the invention is to provide improved means for attaching a dial instrument to a face of a panel in such a manner that the dial of the instrument will be visible through a transparent section of said panel; with which the instrument may be removed and replaced when cleaning, regulation or repairs are required; with which the instrument will be fully inclosed and protected against dust and the natural elements; with which the removal of the instrument may be accomplished in a simple and rapid manner; with which the attachment of the instrument to the panel will be dependably secure and rigid; with which the means by which the instrument is attached to a panel may be made largely from stampings and standard tubular material; with which attachment of the instrument to the panel is accomplished without having objectionable members hooking over the front face of the panel or projecting beyond the edges thereof; and which will be relatively simple, practical and inexpensive.

Various other objects and advantages will be apparent from the following description of several embodiments of the invention, and the novel features will be particularly pointed out hereinafter in connection with the appended claims.

In the accompanying drawing:

Fig. 1 is a front elevation of part of a mirror to which a time piece has been attached in accordance with this invention, and illustrating one embodiment thereof;

Fig. 2 is a transverse, sectional elevation through the same;

Fig. 3 is a fragmentary sectional elevation of the details of Fig. 2, so as to show them on a larger scale;

Fig. 4 is a sectional elevation through a mirror to which a time piece has been at-

tached in accordance with this invention, and illustrating another embodiment thereof;

Fig. 5 is a sectional elevation of a mirror to which a time piece has been attached also in accordance with this invention but illustrating still another embodiment thereof;

Fig. 6 is a sectional elevation on a larger scale of certain details of Fig. 5, particularly the details of the snap connection between the rear plate and the cylindrical shell.

In the embodiment of the invention illustrated in Figs. 1 to 3, the panel in the form of a mirror 10 may be formed of a plate of transparent material such as glass. This plate is provided upon its rear face with an annular groove 11, which has a maximum depth less than the thickness of the plate. An annular member 12 is disposed against the rear face of the plate, which is the face that carries the reflective coating, and at its inner edge is provided with a ring-like flange 13 which extends loosely into and is cemented within the annular groove, so as to be permanently attached thereto. The cement 14 used to fill the groove may be of any suitable type which adheres to the glass or other material of which the plate is formed.

The free end of the flange 13 is provided with an internal, annular sub-flange or rib which provides a shoulder within the cement and thereby a more effective anchorage of the flange within the cement. The outer peripheral surface of the flange 13 may also have grooves or cavities therein into which the cement may enter in order to increase the anchorage on the flange. If desired, a gasket or ring 15 of suitable resilient material such as felt may be interposed between the member 12 and the rear face of the plate so as to provide for limited expansion and contraction of the material of which the member is usually formed, without danger of rupturing the cement or placing undue stresses upon the cement or the plate 10.

The member 12 is provided with a frusto-conical flange 16 having its larger base at its junction with the member 12, and converging rearwardly from the plate. This flange 16 acts as a bezel ring for the dial plate of a

time piece which is confined in close proximity to the member 12 in a manner to be explained presently. An annular ring-like flange 17 extends rearwardly away from the mirror plate 10, from the outer periphery of the member 12. A cylindrical casing or shell 18 is telescopically fitted over the flange 17 of the member 12, so as to form a removable extension thereof, and is removably attached 5 to the flange 17 in any suitable manner such as by screws 19 which are passed through the shell 18 and threaded into the flange 17. The shell 18 is provided with a removable back wall or cover plate 20, which at its periphery is provided with a slight internal flange that snaps into an undercut external peripheral groove at the rear end of the shell 18.

10 A time piece 21 is confined within the shell 18 and against an internal shoulder 22 thereof 20 in any suitable manner, such as by screws 23 which engage with the shell 18 at its free end, and are threaded into a suitable part of the time piece in a manner to draw the time piece against the shoulder 22. The shoulder 22 is 25 so positioned that, when the time piece is confined against it, the dial plate 24 of the time piece will abut or lie in close proximity to the smaller base of the frusto-conical flange 16. The shell 18 may have a suitable aperture 30 through which the winding and setting stem 25 of the time piece may extend.

Referring next to Fig. 4, the mirror plate 10 is provided with an annular groove 11, as previously explained in connection with Figs. 35 1 to 3. A cylindrical ring 26 is disposed endwise against the rear face of the plate 10 with an end section of the ring extending into the annular groove 11 and permanently anchored therein by cement 14. The end of the 40 ring 26 which is within the annular groove may be provided with an internal rib and the external grooves, as explained in connection with Figs. 1 to 3, in order to increase the anchorage of the cement thereon. A cup-like 45 shell 27 telescopes within the outer or free end of the ring 26 and is provided with an external shoulder 28 in the portion outside of the ring 26. A ferrule 29 is threaded upon the outer periphery of the projecting end of 50 the ring 26 and is provided with an internal flange or lip 30 which engages with the shoulder 28 in a manner to draw the shell 27 toward the plate 10.

An annular ring 31 may be disposed within 55 the ring 26 and clamped between the rear face of the plate 10 and the inner end of the shell 27 as the shell is drawn toward the plate 10 by the ferrule 29. The ring 31 is bevelled in the manner shown in Fig. 4 so as to form 60 a bezel ring for the dial of the time piece 32. The time piece 32 is confined against an internal shoulder 33 in the shell 27 in any suitable manner, such as by the screws 34 which pass through the shell 27 and are 65 threaded into the time piece 32. The bottom

or closed end of the shell 27 corresponds to the cover 20 of Figs. 1 to 3 and, if desired, may be made removable, as shown in Fig. 2.

Referring now to Fig. 5, the mirror or plate 10 is provided with an annular groove 11 as in Figs. 1 to 4. A cylindrical shell or ring 35 is provided with an inwardly projecting shoulder 36 adjacent one end, and the inwardly offset end 37 of this frame 35 70 serves as an annular ring section which extends into the annular groove 11. The end or ring section 37 may be provided with the internal rib at its free end and with the external grooves, in the same manner as the flange 13 of Figs. 1 to 3 and the ring 26 of 75 Fig. 4, and is permanently anchored within the groove 11 by suitable cement 38 which fills the groove. A compressible gasket ring 39, such as a felt or rubber, may be interposed 80 between the shoulder portion 36 of the ring 35 and the rear face of the plate 10, so as to serve the same function as the ring 13 of Figs. 1 to 3.

The outer or rear end of the ring 35 may 85 be closed by a removable plate or member 40 which is removably snapped thereon as shown on a larger scale in Fig. 6. An annular ring 41 is disposed against the inner face of the shoulder portion 36 of the shell 35, and is provided with a bevelled face which 90 serves as the bezel for the dial plate of a time piece. A cup-like shell 42 is disposed within the ring 35, with its open end abutting against the ring 41 to confine the latter 95 against the shoulder 36 of the ring 35 and a compressible, resilient pad 43, such as of sponge rubber or felt is disposed between the closed end of the shell 42, and the cover 40 and serves to hold the inner shell 42 resiliently against the ring 41.

A time piece 44 is removably secured in the inner shell 42 so as to be removable through the open end thereof. For this purpose, the inner shell 42 is provided with an internal shoulder 45 adjacent its open end, against which a shoulder of the time piece 44 is drawn by screws 46 which pass through apertures in the closed end of the inner shell and are threaded into the time piece.

Referring now particularly to Fig. 6 it 115 will be noted that the ring 35 is provided at its rearward end with an external groove 47 which is slightly undercut at the end nearest the plate 10, and the closure member 40, which snaps over the ring 35, is provided 120 with a reversely formed internal groove 48, that is, it is reversely undercut and is somewhat deeper than the groove 47, so that when the member 40 is snapped upon the ring 35, the engaging undercut parts of the grooves 125 will draw the member 40 firmly against the bottom of the groove 47 and form a tight joint thereon.

In each embodiment of the invention which 130 has been herein above described and illus-

trated, it will be noted that the dial instrument or time piece is completely enclosed within a housing or case, which has been firmly attached to the rear face of the panel or mirror plate 10. The attaching means is separable so that access to the time piece may be easily obtained and the time piece removed and replaced in a simple manner. The time piece is firmly anchored so that vibration will be avoided and the attachment is free of all parts which extend beyond the edges or over the front face of the mirror plate and create an unsightly appearance.

The subject matter of this application is in the nature of an improvement upon the construction disclosed and claimed broadly in my prior copending application 496,121, filed November 17, 1930, and 497,434, filed November 22, 1930. The subject matter of this application is intended to cover the details not disclosed and claimed in said prior filed applications.

It will be obvious that various changes in the details, which have been herein described and illustrated in order to explain the nature of the invention, may be made by those skilled in the art within the principle and scope of the invention as expressed in the appended claims.

30 I claim as my invention:

1. Means for securing a dial instrument to a face of a panel having a transparent section which comprises a groove in said face, an annular member abutting against said face and having a flange entering and cemented in said groove, a ring extending inwardly from said member adjacent said face of the panel, a casing removably attached to said member, and an instrument removably attached to said casing and disposed against said ring at said face of said transparent section so as to be visible therethrough.

2. Means for securing a dial instrument to a transparent panel which comprises an annular groove in a face of said panel and of a depth less than the thickness of said panel, an annular anchorage member disposed against the grooved face of said panel and having an annular flange-like ring entering and cemented in said groove, said member also having a section extending away from the panel, an enclosure removably anchored to said section, and said dial instrument removably confined within said enclosure and against said member, so as to be visible through said transparent panel, and with the transparent panel forming a weather proof closure for the front of said enclosure and member.

60 3. Means for attaching a dial instrument to a transparent plate, comprising an annular groove in the rear face of said plate, and of a depth less than the thickness of said plate, an annular anchorage member fitted against the rear face of said plate and having

an annular flange entering and cemented in said groove to anchor said member to said plate, said member also having a flange extending rearwardly from the plate adjacent the junction of said annular flange with said member and converging to the rear of said plate to form a frusto-conical bezel ring, said member having an annular flange extending rearwardly thereof, an enclosure member telescoping over and sliding along said last-named flange and removably attached thereto and forming with said member and plate a complete enclosure, and said dial instrument removably confined within said enclosure, with its dial face against the small base 80 of said frusto-conical flange.

4. Means for attaching a dial instrument to a transparent plate, comprising an annular groove in the rear face of the plate, a cylindrical ring disposed endwise against the rear face of said plate and loosely entering and cemented in said groove, a cup-like casing telescoping within said ring and having an external shoulder, a ferrule engaging said shoulder and threaded to the projecting end 90 of said ring for removably confining the casing to said ring, whereby said dial instrument is removably confined within said casing so as to be visible through said plate.
